UNITED STATES PATENT OFFICE.

FRED K. NORTH, OF WINCHESTER, MASSACHUSETTS, ASSIGNOR TO CHAPMAN MANUFACTURING COMPANY, A CORPORATION OF MASSACHUSETTS.

SPINNING-SPINDLE.

1,292,026.

Specification of Letters Patent. Patented Jan. 21, 1919.

Application filed November 18, 1917. Serial No. 202,358.

To all whom it may concern:

Be it known that I, FRED K. NORTH, a citizen of the United States, residing at Winchester, in the county of Middlesex and State of Massachusetts, have invented new and useful Improvements in Spinning-Spindles, of which the following is a specification.

My invention relates to spinning spindles and has for its principal objects power economy by reduction of friction, protection of yarn by improvement in lubrication methods, and greater durability by reason of superior bearing mountings and elimination of delicate parts. These objects I accomplish by providing ball bearings embodying an improved form of raceway, combined with a bolster mounted adjacent its upper extremity upon the base by means adapted to operate as a fulcrum, a spiral centering spring which embraces the tip of the bolster lower extremity and opposes and limits lateral movement of the bolster, a grease cup communicating with the interior of the bolster, and a self adjusting helical spring which bears upon the spindle blade step and maintains a constant and uniform pressure upon both upper and lower bearing balls and normally retains the ball bearing elements in their proper relation. A further contribution to the feature of durability resides in the elimination from my device of the fine threaded stem and adjusting plug in the bolster, as well as all other threaded parts, and the extremely delicate bolster spring formerly employed.

My invention further resides in the particular construction and combination of parts to be hereinafter more fully described and claimed.

In the accompanying drawing in which like numerals of reference indicate corresponding parts in the various figures thereof, Figure 1 is a vertical section of the preferred form of my new and improved spindle; Fig. 2 is a vertical section of the modified form of same adapted to oil lubrication, and Fig. 3 is a detail of my improved ball bearing.

Referring to the drawing, the numeral 1 indicates the spindle base. 2 is the means by which the bolster 4 is mounted on the base and hereinafter referred to as the bolster support, the upper cylindrical section

3 of which frictionally engages the outer

wall surface of the bolster 4 and operates as a fulcrum upon which the bolster swings laterally when taking on the gyratory motion incident to high speed rotation of a spindle blade carrying an unbalanced load. 60 5 is the spindle blade provided at its lower extremity with the cone 12 supported within the bolster 4 upon the balls 6 which are contained in the ball race 7 in the step 8. The step 8 is slidable within the bolster and is 65 provided with a downwardly extending stem 9 the lower end of which is received within the central aperture 10 in the guide 11 fitted within the lower end of the bolster 4 and secured thereto by spinning as shown 70 or any other suitable means. 13 is a helical self adjusting spring which embraces the stem 9, the bottom convolution of which spring rests upon the guide 11, the top convolution bearing upon the shoulder 14 of the 75 step 8 and exerting thereon a yielding pressure sufficient to maintain the parts of the upper ball bearing in the proper relation to each other hereinafter described. The spring 13 further acts as a cushion to absorb 80 shock and protect the lower ball bearing as when an operator holding the blade strikes the spindle base a sharp blow. The guide 11 is also provided with a downwardly extending stem 15 which forms the tip of the 85 bolster and which is embraced in contact by the top convolution of the conical spiral spring 16 and protrudes through the central aperture 17 in the cap 18 which frictionally engages the outer wall of the spindle base 90 and supports the spring 16, the bottom convolution of which is in contact throughout the greater portion of its length with the wall of the cap and the extremity of the base wall and thus held firmly in position. 95 It is to be noted that the upper convolution of the spring 16 is not in contact with the shoulder 19 of the guide 11 and therefore does not exert any longitudinal pressure upon the bolster which receives no support 100 at any point other than the fulcrum 3. The spring 16 thus has no tendency to raise the bolster or permit it to be lowered relatively to the base thus moving the whorl center out of the horizontal plane of the driving band 105 drum. The diameter of the aperture 17 in the cap 18 is substantially greater than that of the stem 15 and thus co-operates with the space between the bolster wall and base wall 110 to permit of lateral movement of the bolster.

in all directions. That portion of the aperture 10 in the guide 11 which lies within the stem 15 is interiorly screw threaded to engage the screw threaded plug 20, by means of which grease is forced up through the well 21 in the step 8 to the interior of the bolster to lubricate the ball bearings upon which the blade 5 is rotated.

The upper bearing in which the blade 5 rotates consists of the cone 23 pressed on the blade, the balls 24, and raceway 22 in ball cup 25. The form of ball race and cone which I employ is an important feature of my invention. In general practice the driving pulleys on a spinning frame are mounted on a horizontal shaft, and rotate in a vertical plane, whereas the spindle whirl rotates in a horizontal plane, producing a quarter turn in the driving band which exerts an upward or downward pull on the blade, depending on the direction of movement of the band. Preferably for the purpose of offsetting the force of gravity a quarter turn which will impart an upward pull is adopted. Owing to the fact that the weight of the blade and other moving parts which it carries is substantially offset by the upward pull of the driving band and the only vertical stress on the bearings is that which results from the pressure of the self adjusting spring, approximately five pounds, while the lateral pull of the driving band ranges up to eight pounds, the greater stress upon the bearing is obviously in a horizontal plane, and the resultant of the two unequal forces, vertical and horizontal, acting upon the bearing at an angle of 90 degrees is not 45 degrees, but approximately 20 degrees to the horizontal. By shaping the curve of the race and cone so that ball diameters intersecting the central points of contact between the race and ball and cone and ball shall with a horizontal plane include an angle of approximately 20 degrees, I obtain the radial thrust through the resultant line of force adapted to enable the bearing most efficiently to perform the required work at the points of severest application. The degree of the proper angle depends upon the variance between the horizontal and vertical stress; the more the former exceeds the latter, the less the angle. For practical purposes however the 20 degree angle will prove highly efficient under conditions usually prevailing, and a bearing constructed as hereinbefore described may be commercially operated with a minimum of friction. Owing to the fact that the pull of the driving band is applied to the blade above the upper bearing, a lever fulcrummed on that bearing is established, and as the distance from the upper bearing to the point of application of power is less than that from the upper bearing to the lower, the horizontal stress on the lower bearing is less

and the form of the bearing relatively unimportant as compared with that of the upper bearing, which sustains the greater burden. The principle of construction however remains the same and it is desirable that it be applied in order to reduce the friction to the least possible degree.

26 is the whirl base the lower portion of which constitutes the whirl 29. The upper portion 30 of the whirl base is centrally apertured and adapted to closely fit the upwardly tapering section 31 of the blade 5 and transmit to the blade the rotative movement of the whirl. 32 is the doffer guard support secured to or (as in Fig. 2) formed integral with the base and provided with the doffer guard 33 pivoted upon the pin 34 and adapted to limit upward movement of the whirl base 26 by contact with the flange 35. 36 is a nut adapted to engage the screw threaded section 37 of the base and firmly secure the latter to the spindle rail of the spinning machine frame.

I have found by experience that grease is on the whole the most satisfactory lubricant for ball bearings, and its application to this art is peculiarly advantageous in that damage to the yarn by spattering of oil is entirely obviated. A further advantage resides in the economy resulting from diminished consumption of lubricant and time and labor ordinarily required in replenishing oil. Accordingly I have shown in Fig. 1 the grease cup type as the preferred form of my new and improved spindle. If, however, for any reason it be desired to employ oil as the lubricant, the type shown in Fig. 2 may be employed without loss of the advantage arising from the other novel features of my invention. Referring to Fig. 2 it will be observed that the only substantial structural differences between the two types reside in the oil inlet 38 in the doffer guard support 32 leading to the oil reservoir 39, whence the oil flows into the base and up through the well 21 into the bolster and is carried to the upper bearing by centrifugal force as the spindle blade is rotated, the shortening of the stem 15, and omission of the grease cup and the opening in the cap 18.

My improved ball bearings coöperating with self adjusting spring and grease lubricating system to permit high speed rotation with a minimum of friction, centering spring 120 acting upon the tip of bolster combined with fulcrum support at top of bolster to permit gyration and eliminate vibration under unbalanced loads, thus further contributing to the reduction of friction, resilient support 125 for the blade which relieves the lower bearing balls from possible shock, and consequent injury, and grease lubrication system insuring protection of material combined to produce a spindle of the highest efficiency and 130

durability, which will spin a yarn of even twist, devoid of oil spots which result in imperfect fabrics, with great rapidity and economy.

5 The method of assembling my new and improved spinning spindle is as follows:

The base is plugged and dipped and the doffer guard 33 mounted on the support 32 and the pin 34 staked. The spiral spring 16 is then placed in the cap 18 and the latter pressed on to the lower end of the base after which the bolster support 2 is pressed into the top of base. Fourteen balls are placed in the upper cup 25 and the blade inserted 15 through a small hole in the cup. The bolster is then placed over the cup 25 and the whole placed in an arbor press with a large part of the press coming down and gripping the large end of bolster forcing it into the die 20 which forms the end over the cup. The bolster and blade are then removed from the press and reversed. Five balls are placed in the race 7 in the step 8 and the latter assembled with spring 13 and guide 11 and inserted in the lower end of bolster which is then placed in a spinning machine for spinning the bolster into a V-shaped recess in the guide. The whirl and whirl base are then forced on to the upper end of blade in an 25 arbor press. The assembly is completed by inserting the bolster in the support 2 in the base with the stem 15 of the guide 11 engaging the spring 16 which has already been inserted as above described.

35 What I claim and desire to secure by Letters Patent is:

1. In a spinning spindle, a base and a bolster mounted thereon by means adapted to prevent longitudinal movement of the bolster relative to the base, combined with a blade step vertically movable within the bolster and yieldingly supported therein.
2. In a spinning spindle, the combination of a base, a bolster supported at a point adjacent its upper extremity by the base and adapted to move laterally in all directions upon said point as a fulcrum, a spring mounted on the base adapted to act upon the

lower extremity of the bolster and oppose lateral movement of the bolster with relation to the base, a step vertically movable within said bolster, a spindle blade mounted in bearings on said step, and a spring adapted to bear upwardly on said step.

3. In a spinning spindle, the combination of a base, a bolster supported at a point adjacent its upper extremity by the base and adapted to move laterally in all directions upon said point as a fulcrum, a spring mounted on the base adapted to act upon the lower extremity of the bolster and oppose lateral movement of the bolster with relation to the base, a step provided with a vertical aperture within said bolster, a plug adapted to force grease through said aperture to the interior of the bolster, and a spindle blade mounted in bearings on said step.

4. In a spinning spindle, the combination of a base, a bolster supported at a point adjacent its upper extremity by the base and adapted to move laterally in all directions upon said point as a fulcrum, a spring mounted on the base adapted to act upon the lower extremity of the bolster and oppose lateral movement of the bolster with relation to the base, a spindle blade mounted in ball bearings on a step vertically movable within the bolster, said step being provided with a vertical aperture and a stem which extends downwardly within a guide secured to the bolster, an exteriorly threaded plug adapted to engage the screw threaded interior of the guide and force grease through said aperture to the interior of the bolster, and a coil spring embracing said stem mounted on the guide and adapted to bear upwardly on said step.

In testimony whereof I have hereunto set my hand in presence of two subscribing witnesses, this twelfth day of November, 1917.

FRED K. NORTH.
